No. 857,183.

PATENTED JUNE 18, 1907.

F. W. LEIDECKER.

WATER GAGE.

APPLICATION FILED JULY 28, 1906.

UNITED STATES PATENT OFFICE.

FRANK WALLACE LEIDECKER, OF MARIETTA, OHIO.

WATER-GAGE.

No. 857,183.

Specification of Letters Patent.

Patented June 18, 1907.

Application filed July 28, 1906. Serial No. 328,256.

To all whom it may concern:

Be it known that I, FRANK WALLACE LEIDECKER, a citizen of the United States, residing at Marietta, in the county of Washington 5 and State of Ohio, have invented a new and useful Water-Gage, of which the following is a specification.

This invention relates to water gages, for boilers and the like, and has for its principal 10 object to provide a gage of simple construction which may be readily taken apart for examination or repairs without shutting down the boiler.

A further object of the invention is to provide a water gage having a valve member 15 arranged to be closed by the fluid pressure from within the boiler and to provide a valve operating means which may be readily detached without permitting the escape of any 20 steam or water.

A still further object of the invention is to provide a gage of this type in which the working parts, that is to say, the valve and its seat, are arranged in a section of a casing that 25 is directly attached to the boiler, while the valve opening means is carried by a separate detachable section which may be removed without difficulty when it becomes necessary to examine the valve.

30 A still further object of the invention is to provide a device of this class in which a pair of separate valve members are employed, one being arranged to close under steam pressure, and the other being movable to 35 closed position by a valve stem or like member.

A still further object of the invention is to provide a device of this class in which a pair of separate valve members are employed, 40 and a movable member is arranged between them for the purpose of transmitting movement from one to the other.

A still further object of the invention is to 45 provide a water gage having a pair of separate valve seats and to arrange between them a movable member by which sediment or scale may be dislodged so as to maintain the water passage clear.

50 A still further object of the invention is to provide a device of this class in which the valve operating stem acts as a reamer for the water passage.

55 A still further object of the invention is to provide a device of this class in which a pair of separate valve members are arranged under the control of a non-circular stem having

one or more relatively sharp edges which serve to scrape the wall of the water passage and thus prevent the accumulation of sediment or scale. 60

With these and other objects in view, as will more fully hereinafter appear, the invention consists in certain novel features of construction and arrangement of parts, herein-after fully described, illustrated in the 65 accompanying drawings, and particularly pointed out in the appended claims, it being understood that various changes in the form, proportions, size and minor details of the structure may be made without departing 70 from the spirit or sacrificing any of the advantages of the invention.

In the accompanying drawings:—Figure 1 is a sectional elevation of a water gage constructed in accordance with the invention. 75 Fig. 2 is a transverse sectional view of the same on the line 2—2 of Fig. 1. Fig. 3 is a similar view on the line 3—3 of Fig. 1. Fig. 4 is a detail sectional view on an enlarged scale of the valves and valve seats. Figs. 5 80 and 6 are similar views illustrating modifications of the valve and valve seat structure. Fig. 7 is a view corresponding to Fig. 3, illustrating a slightly modified form of valve stem. 85

Similar numerals of reference are employed to indicate corresponding parts throughout the several figures of the drawings.

The casing of the gage is divided into 90 three sections 10, 11 and 12. The first section 10 is provided with a tapered thread 15 which screws into a threaded opening formed in the boiler shell, and is further provided with a cylindrical portion that extends well 95 into the boiler and carries the valves. The section 10 has a wrench engaging member 16 so that it may be readily screwed into place, and is further provided with a female thread for the reception of the threaded end of the 100 central section 11. This section 11 carries a downwardly extending nozzle 17 through which the water or steam may flow when the gage is open. The outer section 12 has a threaded connection with the outer end of 105 the central section 11 and is provided with a threaded opening for the reception of the threaded portion of a valve stem 18, the latter carrying a handle 19 of any type for convenience in turning the stem and opening 110 and closing the valve.

The inner portion of the section 10 is

bored out to form two valve seats 20 and 21 and two valve chambers 22 and 23, these being connected by a passage 24 that is of less diameter than either of the chambers. In 5 the inner chamber 22 is arranged a pressure closed valve 25 which may take the form of a ball, and this ball being exposed to the boiler pressure may be driven against its seat 20 when the stem is moved out, forming a tight 10 joint and preventing the escape of any steam or water from the boiler, the structure being such that when in this position the central section 11 and outer section 12 of the gage may be readily detached without drawing 15 the fires. The inner ball 25 is held within the chamber 22 by a pin 27 which will prevent the ball from falling within the boiler. In the outer valve chamber 23 is arranged a manually closed valve 28 which may, also, 20 be of the ball type, this valve being engaged by the inner end of the stem 18 and being forced against its seat 21 by the turning of the stem.

In the small passage 24 between the two 25 valve chambers is a ball 30 of smaller diameter than the passage and that serves as a means for communicating movement from one valve to the other. This intermediate movable member 30 will force the valve 25 30 from its seat when valve 28 is forced to closed position. When the stem is moved outward, and valve 28 is free, the valve 25 is forced to its closed position by the pressure from within the boiler, and the intermediate member 30 then forces the valve 28 from its seat. By turning the stem 18 inward to a limited extent, both valves may be held from their seats, and a quantity of water or steam allowed to escape from the boiler. This intermediate movable member 30 by playing back and forth in the passage 24 serves to dislodge any sediment or scale, so that it 40 may be washed out by the passage of the water or steam.

45 That portion of the central section 11 of the casing which carries the nozzle is provided with an inner bore 32 of small diameter, and an outer bore 33 of somewhat large diameter, and the outer bore serves as a 50 guide and support for a cylindrical enlargement 35 at the inner end of the threaded portion of the stem. That portion of the stem extending inward from the enlargement 35 to the valve is non-circular in form in cross 55 section and is provided with a relatively sharp edge or edges to serve as a reamer for the smaller bore 32 as the valve stem is turned, thus preventing the accumulation of sediment or scale. The stem may be square 60 in cross section, as shown in Fig. 3, or it may be of any other form, a tri-angular form being illustrated in Fig. 7, so long as it presents one or more relatively sharp edges to serve as a scale remover.

In the construction shown in Fig. 5, the 65 valves 25^a and 28^a are in the form of disks, and the intermediate member 30, which is placed between them, serves as a means for transmitting movement from one to the other.

70 In the construction shown in Fig. 6, the ball valves 25 and 28 are retained and the intermediate member 30^a is in the form of a spider similar to the devices ordinarily employed as valve stem guides or any other connecting means may be employed for the purpose of transmitting movement from one valve to the other, and ball, disk or other forms of valve may be employed without departing from the invention.

75 The device may be used to advantages in connection with pressure gages, gage gas cocks, and other devices which are connected to boilers or other reservoirs containing fluid under pressure, and which it may become necessary to remove or replace at any time.

80 I claim:—

1. In a device of the class described, a valve casing formed of a pair of detachable sections, the inner of which is arranged for connection with the boiler, and is provided with a valve seat, a loose valve movable under boiler pressure to closed position against the seat and serving to prevent the passage of fluid from the boiler when the outer section of 95 the casing is detached.

2. In a device of the class described, a valve containing casing adapted to communicate with the boiler and having a pair of valve seats, a pressure closed valve movable 100 against one of the seats, a second valve, manually operable means for moving the same against the other seat, and a loose member arranged between the valves and adapted to transmit movement from one to 105 the other.

3. In a device of the class described, a casing having a pair of valve seats facing in opposite directions, respectively, a pair of valves, one of which is movable by pressure 110 against its seat, a manually operable means for moving the second valve to its seat, and a loose ball arranged between the valves and serving as a means for transmitting movement from one to the other.

115 4. In a device of the class described, a casing having a pair of spaced valve seats and provided with a contracted passage way between the seats, a pair of ball valves one of which is movable against its seat by fluid 120 pressure, a manually operable means for moving the other valve against its seat, and a loose member arranged in the contracted passage way and serving as a means for transmitting movement from one valve to the 125 other.

5. In a device of the class described, a valve casing including detachably connected

inner and outer sections, the inner section having a valve seat, a fluid pressure closed valve carried by the inner section and arranged to close against said seat and prevent the escape of fluid when the outer section is detached, and a separate stem for closing said valve, said stem being carried by the outer section.

In testimony that I claim the foregoing as my own, I have hereto affixed my signature to in the presence of two witnesses.

FRANK WALLACE LEIDECKER.
